UNITED STATES PATENT OFFICE

ROBERT UHDE, OF KASSEL-WILHELMSHOHE, GERMANY, ASSIGNOR TO SCHMIDT'SCHE HEISSDAMPF-GESELLSCHAFT MIT BESCHRANKTER HAFTUNG, OF KASSEL-WILHELMSHOHE, GERMANY, A CORPORATION OF GERMANY

SUPERHEATER HEATED BY SUPERHEATED STEAM

Application filed October 23, 1929, Serial No. 401,920, and in Germany November 3, 1928.

The invention relates to superheaters, especially interstage superheaters, heated by superheated steam, in which the heating steam gives up its superheat in a first zone 5 and its heat of evaporation, wholly or in part, in a second zone.

The construction of such superheaters presents difficulties in practice due to the fact that special conditions must be satisfied in the 10 two zones in order that heat transmission from the heating steam to the steam to be superheated may be as efficient as possible.

In the first zone, in which the heating steam gives up its superheat to the steam already superheated to a certain extent in the 15 second zone, it is necessary in every case in order to obtain the highest possible superheat for the steam to be superheated, that the latter should be heated by hotter and hotter steam as its temperature rises from point to point along its path.

This requirement is satisfied if the steam to be superheated flows throughout the first zone in countercurrent to the heating steam.

25 In the second zone, the temperature of the heating steam and its condensate remains substantially uniform over the whole length of the heating tube system so that, at least as regards the available fall of temperature, it is of no consequence whether the steam to be superheated flows in the opposite direction to or in the same direction as the heating medium.

On the other hand, in order to obtain efficient transmission of heat in this zone, it is 35 essential that the velocity of flow of the steam to be superheated should be high.

This requirement is satisfied in the second superheater zone by reducing the cross-sectional area of flow for the steam to be superheated by help of partitions so arranged that the steam to be superheated experiences one or more changes of direction as it flows through this zone.

45 In superheaters of the kind in question, the invention accordingly makes it possible to utilize efficiently the space available and at the same time to attain a comparatively high temperature of superheat for a given 50 heating surface by leading the steam to be su-

perheated throughout the first zone in countercurrent to the heating steam so as to utilize the available temperature drop efficiently and through the second zone along an extended path with one or more changes of direction obtained by help of partitions, so as to provide for small cross-sectional areas of flow and therefore a high velocity of the steam to be superheated.

55 Referring to the accompanying drawings:

Figure 1 shows diagrammatically a longitudinal vertical section of one form of the invention, while

Figure 2 shows likewise in vertical longitudinal section a practical construction of an interstage heater in which the space within the container is advantageously utilized and the heating surface favorably distributed.

60 In Figure 1, the superheater container is denoted by the numeral, 1, the steam to be superheated entering at the bottom by the inlet, 2, while the superheated steam leaves at the top by the outlet, 3. Heating coils, 4, are provided, to the upper ends, 5, of which the superheated heating steam is led, the condensate flowing away from the lower ends, 6.

65 The lower part of the superheater is subdivided by vertical partitions, 7 and 8, of which the partition, 8, is connected at its upper end to a transverse wall, 9, and ends a certain distance above the bottom, 10, of the container, 1, while the partition, 7, starts from the bottom, 10, of the container and stops a certain distance below the transverse wall, 9. This transverse wall extends over the greater part of the breadth of the container and is arranged at about the level where the heating steam passing through the coils, 4, 75 has given up its superheat and passed into the saturated state.

80 The chamber corresponding to the first zone of the superheater in which the steam in the heating coils gives up its superheat to the surrounding interstage steam thus lies above the transverse wall, while below this wall lies the chamber corresponding to the second superheater zone in which the heating steam gives up its heat of evaporation, wholly or in part, and is correspondingly condensed.

If the arrangement of the two superheater zones in a common container makes the apparatus too cumbrous and bulky, two separate containers may be provided, one for each zone.

The steam to be superheated, as shown in Figure 1, flows through the second, i. e., the lower zone of the superheater, with two reversals of direction, its velocity being comparatively high because the cross-sectional areas available for flow are small in consequence of the sub-division of the container by the partitions.

In the first or upper zone, the pre-superheated steam flows throughout in the opposite direction to the heating steam and therefore the pre-superheated interstage steam definitely increases its temperature of superheat along the whole length of its path through this zone to the outlet.

In the form of the invention shown in Figure 2, the superheater container is formed in two sections, the upper section, 11, forming a chamber serving for the first zone, in which the heating steam gives up its superheat, and the lower section, 12, forming a chamber for the second zone, in which the heating of the interstage steam is effected by the heat of evaporation of the heating steam.

The inlet connection, 13, for the interstage steam to be superheated is arranged at the upper end of the section, 12, of the container and the outlet connection, 14, for the superheated interstage steam at the upper end of the section, 11, of the container.

In the lower section, 12, a cylindrical partition, 15, is arranged which is provided with feet, 16, resting on the bottom, 17, of the container, openings, 18, of sufficient size being provided between the feet for the passage of the interstage steam, as shown by the arrows. The cylindrical partition, 15, is carried up as far as the joint between the two container sections, 11 and 12, that is, as far as the plane of separation of the two superheater zones, and is connected at this level to a horizontal transverse wall, 19, which is formed as a two-part ring forming a cover to the space between the cylindrical partition, 15, and the wall of the container section, 12.

The superheated heating steam flows through heating coils, 20 and 21, arranged concentrically in the container, the upper ends of all these coils issuing from a chamber, 24, provided in the end, 23, of the container, the chamber, 24, being shut off from the interior of the container by a plate, 25, and receiving the superheated heating steam through the inlet 26.

A corresponding chamber, 28, in communication with the outlet, 29, for the heating steam, is provided in the bottom, 17, of the container, the inner heating coils, 20, which run uniformly through the two zones of the container being connected to this chamber.

The two outer coils, 21, in the first superheater zone are interwound in such a way that their convolutions lie on the surface of a common cylinder but after passing into the second zone they are rearranged in the form of two concentric helices lying one within the other and are connected at their lower ends to an outlet, 30, provided in the container wall.

In order to prevent flow of interstage steam through the space within the heating coils, an obturator, 31, is provided taking the form of a closed cylinder of sheet metal.

By means of the cylindrical partition, 15, the interior of the second superheater zone is sub-divided so that the heating surface arranged in this space is traversed by the steam to be superheated at a comparatively high velocity. The cross-sectional area of that part of the second zone lying within the partition, 15, is approximately equal to the cross-sectional area of the first superheater zone, which the steam to be superheated passes through in counter-current to the heating steam, and as a consequence, on passing from the second into the first zone, no substantial alteration of velocity occurs, especially when it is borne in mind that the volume of the interstage steam increases with increasing superheat.

Due to the fact that the convolutions of the two outer coils, 21, in the first zone are wound into one another and in the outer section of the second zone lie one within the other, a uniform distribution and compact arrangement of heating surface are secured.

What I claim is:

1. A superheater heated by superheated steam comprising a container divided into two chambers, tubular heating coils for superheated heating steam passing through said chambers, the first of the chambers being adjacent the inlet side of said heating coils and the second of said chambers being adjacent the outlet side of said heating coils, said second chamber having an inlet opening for the steam to be superheated and said first chamber having an outlet opening for the steam to be superheated at the side adjacent the inlet of said heating coils, said second chamber communicating with said first chamber at the side adjacent the intermediate portion of said heating coils, and partitions dividing said second chamber into a plurality of connected sections, said partitions being so arranged as to provide a tortuous path of reduced cross section for the steam to be superheated through said second section, whereby the steam to be superheated passes through said second section at a high velocity in heat exchange relation to the heating steam in the second part of its path and then through the first section in heat exchange and counter current relation to the heating steam in the first part of its path, said hea-

ing steam giving up its superheat in the first part of its path and its heat of evaporation in the second part of its path.

2. A superheater as claimed in claim 1 wherein the partitions are arranged to divide the second chamber into two sections, one of which is in direct connection with the first said chamber, some of the heating coils running uniformly through the first chamber and that section of the second chamber directly connecting with the first chamber, and other of the heating coils having interwound convolutions lying one above the other in the first chamber and convolutions concentrically arranged but of different radius in that section of the second chamber which is separated by the partitions from the section directly connecting with the first chamber.

20 In testimony whereof I have affixed my signature.
